Primary Examiner — Leanne Was-Englehart*Assistant Examiner* — Alison Davis(74) *Attorney, Agent, or Firm* — IP Spring(57) **CLAIM**

The ornamental design for a TV stand, as shown and described.

DESCRIPTION

FIG. 1 is a front view of a TV stand showing our new design; FIG. 2 is a rear view thereof;

FIG. 3 is a left side view thereof;

FIG. 4 is a right side view thereof;

FIG. 5 is a top view thereof;

FIG. 6 is a left, front perspective view thereof; and,

FIG. 7 is a right, rear perspective view thereof.

The portions shown in broken lines form no part of the subject design; the claimed TV stand is shown in solid lines.

1 Claim, 7 Drawing Sheets(56)
